TYPOGRAPHICAL SLUG CASTING MACHINE

Hermann Brandenburg, Berlin-Tempelhof, Germany, assignor to Mergenthaler Linotype Company, Brooklyn, N. Y., a corporation of New York

Application May 3, 1940, Serial No. 333,087
In Germany May 15, 1939

10 Claims. (Cl. 199—50)

This invention relates to typographical slug casting machines such as those known commercially under the registered trade mark "Linotype"; wherein, when a composed line of matrices and spacebands is presented to the front of a mold, it is positioned between a pair of vise jaws and while so positioned is expanded or justified by the expansion of the spacebands which are driven up through the line by a justification bar prior to the casting operation.

More particularly, the invention relates to such machines as are equipped with a quadding and centering device whereby the cast type may be offset at one or both ends of the slug or type bar. In such machines, as is also the case with machines which are not so equipped, it is necessary to change the length of the slugs produced and accordingly of the matrix line according to the width or measure of the page or column to be printed. For this purpose the mold slot in which the slugs are cast is made variable in length, and one of the vise jaws, in usual practice the left-hand one, is also made adjustable to correspond, so that lines of one length or another may be used as required.

In known constructions of this kind, one of the vise jaws is usually constructed in such a manner that the vise jaw proper is capable of sliding relatively to a jaw block which is coupled to the operating mechanism of the device. In this arrangement the vise jaw is connected to the jaw block by a locking member in the form of a rack bar which is adapted to engage resiliently in a correspondingly toothed surface. By pressing the locking member in a downward direction the locking mechanism is released and the vise jaw may then be moved relatively to the jaw block. The jaw is thus adjusted to the desired line measure, a scale and a longitudinally movable pointer being provided on both of the said parts for the purpose of adjustment.

In this known arrangement, the locking members are subjected to strains arising from the pressure exerted upon the jaws when line justification takes place. To these strains must be added blow-like vibrations caused by the sudden contact of the jaws with each other when blank slugs are cast. Further, as there is only a small amount of space available for the locking member and for the parts associated with it, tempered parts made from an expensive metal must be used which, as has been proved in practice, frequently break and give rise to stoppages. Moreover, the inaccessibility of the locking member for longitudinal adjustment of the jaw is a

disadvantage and the said adjustment cannot be effected from the operator's seat in front of the machine.

The invention provides an adjusting mechanism for the vise jaws by which the disadvantages hereinbefore described are eliminated. It consists in a typographical slug casting machine of the kind referred to having a quadding and centering device for adjusting the matrix line length wherein a separate adjustment for one of the vise jaws is provided by means of a single adjustable rod passing through the said vise jaw.

Preferably the rod and the vise jaw to be adjusted are mounted in such a manner that the strain caused by the adjustment is distributed throughout the length of the vise jaw. In a preferred construction one of the vise jaws is arranged so as to be displaceable, in relation to a guiding carriage which is connected to the operating mechanism of the line quadding and centering device, by means of a screw threaded rod, the adjustment of the said rod being effected from a stationary part of the machine. For this purpose the screw threaded rod may, at one end, be rotatably mounted in the said guiding carriage which is conveniently arranged so as to be longitudinally displaceable and the other end of the said rod may be arranged to project telescopically into a stationary sleeve in common with which the rod is rotatable by means such as an adjusting wheel.

This construction allows the adjusting mechanism to be fixed at a convenient distance from the jaw proper in a position which is easily accessible from the operator's seat, while the strains occurring when the vise jaws become operative are spread over the screw thread which extends along the entire length of the jaw.

The invention will now be described in greater detail with reference to the accompanying drawings which illustrate one constructional form which it may assume. In the said drawings:

Figure 1 is a front elevation partly in section of vise jaw adjusting mechanism of a typographical slug casting machine of the kind to which the invention relates;

Figure 2 is a plan view of the said mechanism partly in section;

Figure 3 is a side view of the mechanism represented in Figure 1, showing the adjusting scale;

Figure 4 is a section through the adjusting rod on the line A—A of Figure 2, and

Figure 5 is a section through the adjusting rod sleeve on the line B—B of Figure 2.

Referring to the drawings, 1 and 2 are the vise

jaws of a line quadding and centering device of a typographical slug casting machine of the kind referred to, whereof the upper portion only of the operating mechanism is shown in Figure 1. The jaws 1 and 2 are actuated by the operating mechanism through the quadding links 3, and quadding levers 4. The said quadding levers are adapted to be coupled in known manner to the vertical quadding rod 5 by means of the quadding rod control collar 6. The vise jaws 1 and 2 are rigidly connected to the jaw blocks 7 and 8. The jaw block 7 to which the jaw 1 is fast, is longitudinally displaceable in relation to a guiding carriage 9 which ensures that the jaw 1 is capable of being independently adjusted in a longitudinal direction. The guiding carriage 9 is in turn connected to one of the quadding levers 4 of the operating mechanism of the quadding and centering device by means of one of the quadding links 3. The jaw 2 is directly attached to the other quadding link 3 which is secured to the other quadding lever 4 by means of its jaw block 8.

The displacement of the jaw 1 and the jaw block 7, relatively to the guiding carriage 9 is effected by means of the jaw adjusting rod 10 which is provided with a threaded portion 11, such portion being adapted to engage a longitudinally threaded opening in the jaw block 7. The jaw adjusting rod 10 is also formed with a cylindrical end 12 which extends beyond the threaded portion 11 and which is rotatably mounted in the guiding carriage 9 but is not longitudinally displaceable therein. The other end of the jaw adjusting rod 10 engages in a sleeve 13 which extends through a longitudinal aperture in the jaw block 8. The end of the said sleeve 13 is rotatably mounted in a fixed part of the machine, such for instance as the vise top 14.

The jaw adjusting rod 10 in consequence of its attachment to the guiding carriage 9 moves longitudinally therewith and is slideable within the sleeve 13. The jaw adjusting rod 10 is advantageously provided with a flattened portion (see Figure 4) which engages with a similar flat 15 in the interior of the sleeve 13, as shown in Figure 5. The rod 10 is slideable in relation to the sleeve 13 along these flattened surfaces which also serve to enable rotary movement of the sleeve 13 to be imparted to the rod 10.

The rotation of the sleeve 13 is effected by the operation of gear wheel 16 which is also located in the upper part of the vise top 14. The gear wheel 16 is fitted with a gear wheel handle 17 and its teeth engage with those on a gear wheel 18 which in turn engages with a pinion 19 which is rigidly connected to the sleeve 13. When the gear wheel 16 is rotated, the sleeve 13 and consequently also the jaw adjusting rod 10 is rotated by the intermediate gears 18, 19, thereby causing the vise jaw 1 and its jaw block 7 to be longitudinally displaced. In the construction illustrated in the drawings the rod 10 is provided with a thread having a nonpareil (6 point) pitch and the gear wheel 16 is provided around its periphery with a divided scale having 24 sectional markings equivalent to 2 ems per revolution; consequently, the selected transmission ratio between the sleeve and the gear wheel is 1:4.

The gear wheel 16 moreover drives through gear mechanism 20 an indicator drum 21 which is mounted upon the same shaft as the gear wheel, the said drum being provided around its periphery with scale divisions serving to indicate

the maximum line measure divided into 2 em sections.

The invention is not restricted to the constructional form illustrated, but alterations in some details may be carried out without going beyond its scope. If desired, for instance, the adjustment may be carried out directly upon the vise jaw 1 or the jaw blocks 7 or 8, and other displacement and operating means may also be employed within the scope of the claims which permit an adjustment of the jaws by allowing for the varying distance of movement of the holder.

Having described my invention, I declare that what I claim and desire to secure by Letters Patent is:

1. In a slug casting machine of the kind referred to the combination of a pair of line-clamping vise jaws, mechanism for adjusting said jaws relatively to one another for quadding and centering, a rotary adjusting rod in screw threaded engagement with one of said jaws and means for rotating said rod to effect separate adjustment of said jaw, said means including a rotatable element telescopically connected to the rod.

2. In a slug casting machine of the kind referred to the combination of a pair of line clamping vise jaws, means for adjusting said jaws relatively to one another for quadding and centering, a guiding carriage connected to said mechanism, a rotary adjusting rod connected to said guiding carriage and engaging with one of said jaws by means of a screw thread and means for rotating said rod while permitting the rod to move longitudinally as a unit with the guiding carriage.

3. In a slug casting machine of the kind referred to, the combination of a pair of line clamping vise jaws, mechanism for adjusting said jaws relatively to one another for quadding and centering, a guiding carriage connected to said mechanism, a rotary adjusting rod connected to said guiding carriage and engaging one of said jaws to be separately adjusted by means of a screw thread connection, said rod passing through the other of said vise jaws and means for

45 rotating said rod while permitting the rod to move longitudinally as a unit with the guiding carriage.

4. In a slug casting machine of the kind referred to, the combination of a pair of line clamping vise jaws, mechanism for adjusting said jaws relatively to one another for quadding and centering, a guiding carriage connected to said mechanism, a rotary adjusting rod connected to said guiding carriage and engaging one of said jaws to be separately adjusted by means of a screw thread connection, a sleeve rotatably mounted in the other of said vise jaws, said rod being slidably engaged in said sleeve, and means for rotating said sleeve.

5. In a slug casting machine of the kind referred to, the combination of a pair of line clamping vise jaws, mechanism for adjusting said jaws relatively to one another for quadding and centering, a guiding carriage connected to said mechanism, a rotary adjusting rod connected to said guiding carriage and engaging one of said jaws to be separately adjusted by means of a screw thread connection, a sleeve rotatably mounted in the other of said vise jaws, a flattened surface on said rod, a corresponding interengaging flattened surface in said sleeve, said rod being slidably engaged in said sleeve, and means for rotating said sleeve.

6. In a slug casting machine of the kind referred to the combination of a pair of line

clamping vise jaws, means for adjusting said jaws relatively to one another for quadding and centering, a guiding carriage connected to said mechanism, a rotary adjusting rod connected to said guiding carriage and engaging with one of said jaws by means of a screw thread, a pinion mounted on said rod, gearing connected to said pinion and a gear wheel connected to said gearing to rotate said rod while permitting it to move longitudinally as a unit with the carriage.

7. In a slug casting machine of the kind referred to the combination of a pair of line clamping vise jaws, means for adjusting said jaws relatively to one another for quadding and centering, a guiding carriage connected to said mechanism, a rotary adjusting rod connected to said guiding carriage and engaging with one of said jaws by means of a screw thread, a pinion mounted on said rod, gearing connected to said pinion, a gear wheel connected to said gearing to rotate said rod, while permitting it to move longitudinally as a unit with the carriage, and an indicator drum connected to said gear wheel, said drum being marked with indications of varying line lengths.

8. In a slug casting machine of the kind referred to the combination of a pair of line clamping vise jaws, mechanism for adjusting said jaws relatively to one another for quadding and centering, a guiding carriage connected to said mechanism, a rotary adjusting rod connected to said guiding carriage and engaging one of said jaws to be separately adjusted by means of a screw thread connection, a sleeve ro-

35 said rod being slidably engaged in said sleeve, gearing connected to said sleeve to rotate the same, and a gear wheel driving said gearing.

9. In a slug casting machine of the kind referred to the combination of a pair of line clamping vise jaws, mechanism for adjusting said jaws relatively to one another for quadding and centering, a guiding carriage connected to said mechanism, a rotary adjusting rod connected to said guiding carriage and engaging one of said jaws to be separately adjusted by means of a screw thread connection, a sleeve rotatably mounted in the other of said vise jaws, said rod being slidably engaged in said

15 sleeve, a pinion mounted on said sleeve, step up gearing connected to said pinion, and a gear wheel connected to said gearing to rotate said rod.

10. In a slug casting machine of the kind referred to the combination of a pair of line clamping vise jaws, mechanism for adjusting said jaws relatively to one another for quadding and centering, a guiding carriage connected to said mechanism, a rotary adjusting rod connected to said guiding carriage and engaging one of said jaws to be separately adjusted by means of a screw thread connection, a sleeve rotatably mounted in the other of said vise jaws, said rod being slidably engaged in said

30 sleeve, gearing connected to said sleeve to rotate the same, a gear wheel driving said gearing, and an indicator drum connected to said gear wheel, said drum being marked with indications of varying line lengths.

HERMANN BRANDENBURG.
